UNITED STATES PATENT OFFICE.

HENRY J. GALLUP, OF POQUETANUCK, CONNECTICUT.

CARTRIDGE-RELOADING TOOL.

SPECIFICATION forming part of Letters Patent No. 472,990, dated April 19, 1892.

Application filed June 29, 1891. Serial No. 397,819. (No model.)

To all whom it may concern:

Be it known that I, HENRY J. GALLUP, a citizen of the United States, residing at Poquetanuck, in the county of New London and State of Connecticut, have invented certain new and useful Improvements in Cartridge-Reloading Tools, which improvements are fully set forth and described in the following specification, reference being had to the accompanying two sheets of drawings.

My invention relates to the class of bench and hand tools used for decapping, recapping, and recharging cartridge-shells, and has for its object the production of a serviceable, powerful, and convenient tool at a moderate cost. My new form of tool is capable of performing various services—such as, for example, removing the old primer, reseating the new primer, resizing the open end of the cartridge-shell, measuring a sufficient charge of powder, and delivering it into said shell and also forcing home the bullet or wad, as the case may be.

To explain more clearly my invention, I have provided the annexed drawings, in which—
Figure 1 is a side elevation of my improved reloading-tool; and Fig. 2, a similar view partly cut away to expose the internal arrangement of parts, the operating-handle being depressed as in the act of forcing out the old primer and ramming home a new charge in the shell. Fig. 3 is a view substantially like Fig. 2, but shows the operating-handle elevated and as in the act of forcing a new primer into its seat in the cartridge-head. Fig. 4 shows portions of the main frame and the sliding section seated thereon, showing the lever *g*, which supports the shell during the operation of reloading, as swung around at right angles to said main frame, to release said shell. Fig. 5 is an enlarged view, principally in section, of the parts shown in Fig. 4. Fig. 6 shows a portion of bed *a* with an opening *a'* of taper form.

In the drawings, the letter *a* denotes the main frame or bed section of my device, having its lower portion formed to slip over the projecting edge of a table and provided with a binding-screw, as *b*, by which said device may be securely clamped in a given position.

c denotes a slide-block located and arranged to slide lengthwise on the bed-section, being held in proper position by clips *d*, which straddle said slide-block and are secured to the bed

by screws *e*. A bar or plate *e'* connects the clips *d*, and on this bar is a cup *f*, which serves as a receptacle for powder during the operation of loading. The bar *e'* is provided with an opening which, when the said bar is in its rearmost position, as in Fig. 2, is coincident with the mouth of cup *f*, and serves to receive and measure exactly a charge of powder necessary for reloading a shell. When the slide-block is moved forward on section *a*, as in Fig. 3, the charge of powder thus measured is brought immediately over a cartridge-shell, which has been inserted from the under side of said section *a*, and the powder drops by gravity into said shell. The cartridge-shell is suitably supported by a lever *g*, which is secured to section *a* by a screw *g'*, the screw being loosely fitted in the lever, so that the latter may rock slightly on its fulcrum. The outer end of lever *g* is bent upward around the end of the bed-section *a* and terminates in a beveled end that is in the path of a handled bar *h*. The rear end of this bar is hinged to a lever *i*, whose lower end is hinged to an extension of the bed-section *a*, the bar *h* being thus free to be moved longitudinally a limited distance and to be raised and lowered at its handle end. The lever *i* is connected near its middle with the slide-block *c*, and it will be understood that when the bar *h* is moved longitudinally the slide-block is correspondingly moved. The front end of the slide-block (right-hand end, as here shown) is formed with an upwardly-projecting stud *k*, whose upper portion for a distance nearly equal to the length of the cartridge-shell is straight and of such diameter that it may fit snugly a shell placed thereon. Below this straight portion the stud *k* is tapered, as shown, so that when the shell is forced downward on the stud the mouth of the shell may be slightly spread or expanded. Within stud *k* is a loosely-fitting pin *k'*, whose lower end rests on the bottom wall of an inclined slot *k''*, cut in the bed-section *a*, the length of said slot being a little more than the longitudinal movement of the slide-block. The length of pin *k'* is such that when it rides up to the highest point of the inclined slot the upper end of said pin projects above the stud *k* a distance fully equal to the thickness of the cartridge-primer. Stud *k* and its sliding pin

k' are used during the operations of decapping and recapping a shell. When it is desired to decap a shell, it is placed on a stud *k*, as in Fig. 5, and bar *h* is forced downward 5 until it rests on the cartridge-head, a portion of said bar being cut away or notched, as at *h'*, to provide a cavity immediately over the primer. When bar *h* is depressed and the cartridge-shell forced downward on stud *k*, the pin *k'*, lying in the path of the primer, checks the latter and forces it up into recess *h'*, from which it drops when bar *h* is raised. Said bar is then drawn forward—that is, toward the right hand, as shown in Fig. 3—15 when pin *k'* drops by gravity to the lowest point of the inclined slot *k*². A new primer may then be entered in the head of the shell and pressed home by a stud *h*², that is secured to bar *h* and projects downward therefrom, 20 the end of said stud being of about the same diameter as the primer. The position of the different parts during the operation of recapping is shown in Fig. 3.

The powder-cup *f* is formed at one side with 25 lateral extensions *f'* *f*², which are bored to provide bearings for a vertical rod *m*, which forms the plunger or ramrod of my device. This plunger is forked at its upper end to straddle the rod *h* and is secured thereto by 30 a pin or screw *m'*, which passes through a slot *h*³ in rod *h*. When said rod is moved longitudinally, the plunger is not disturbed; but when the rod is raised or lowered the plunger is correspondingly moved. Plunger *m* is thus 35 supported at all times in vertical alignment with an opening *a'* in the bed *a*, in which the cartridge-shells are supported during the operation of reloading. The opening *a'* may, if desired, be slightly reduced in diameter just 40 at the point where the end of the shell comes, so that when the rod *h* and the plunger *m* are forced downward to set the bullet home and the lever *g* crowds the cartridge-shell upward into the opening *a'* the end of the shell 45 will be slightly closed or crimped on and around the bullet, thus serving in a measure

to resize each shell after loading. Such a form of opening *a'* is shown in Figs. 6 and 7.

Means for swaging the bullet are also provided, and illustrated in said Figs. 6 and 7, as follows: The hole in the slide-block *c*, through which the plunger *m* passes during the act of "setting" the ball, is tapered slightly from the upper end, the lower portion of said hole being exactly the size which the ball should be 55 when swaged. When the ball is dropped into the hole and forced downward through it, said ball is swaged down to a size that corresponds exactly to the inner diameter of the shell, and this being performed during the 60 act of loading no time is lost nor special effort required to accomplish such swaging.

Having described my invention, I claim—

1. In a reloading-tool, in combination with a bed-section, a block mounted to slide on 65 said bed bearing a stud *k* to receive a cartridge-shell, a decapping-pin within said stud, as set forth, (the bed being formed with an inclined wall *k*², on which the lower end of said decapping-pin rests,) and a lever *h*, connected with both the bed and slide-block in manner as set forth and provided with a notch *h'*, which is coincident with the stud *k* when the slide-block is moved in one direction, and with a rod or projection *h*², which is coincident with said stud when the slide-block is moved in the opposite direction, all being substantially as and for the purpose specified. 70

2. In combination with a bed-section having opening to receive a cartridge-shell, a handled rod *h*, connected with said bed, as set forth, a longitudinally-movable plunger *m*, coincident with said opening and connected to said handled rod, and a lever *g*, hung at the under side of said bed, one end of said lever 80 being bent upward into the path of rod *h*, all being substantially as and for the purpose specified. 75

HENRY J. GALLUP.
